UNITED STATES PATENT OFFICE.

JOSEPH H. ROACH, OF BROOKLINE, PENNSYLVANIA; WALTER T. ROACH EXECUTOR
OF SAID JOSEPH H. ROACH, DECEASED.

STOKER FURNACE.

Application filed December 18, 1919. Serial No. 345,816.

To all whom it may concern:

Be it known that I, JOSEPH H. ROACH, a citizen of the United States, residing at Brookline, in the county of Delaware and 5 State of Pennsylvania, have invented certain new and useful Improvements in Stoker Furnaces, of which the following is a specification.

This invention relates to stoker furnaces 10 and has for an object to provide a stoker having improved means for introducing fuel to and regulating it upon the grate surface, together with means for varying the air pressure supplied to different areas of 15 the ignited fuel.

Referring to the accompanying drawings, which are made a part hereof, and on which similar reference characters indicate similar parts,

20 Figure 1 is a longitudinal sectional view of a furnace taken through the retort on line 1—1 of Figure 2,

Figure 2 is a transverse sectional view taken on line 2—2 of Figure 1,

25 Figure 3 is a horizontal sectional view taken on line 3—3 of Figures 1 and 2,

Figure 4 is a top plan view of a fragment of the grate surface as indicated by arrow 4 at Figure 2,

30 Figure 5 is a detail sectional view through the grate surface as indicated by line 5—5 of Figure 4,

Figure 6 is a top plan view of the rock-shaft operating mechanism,

35 Figure 7 is a view of the rock-shaft operating mechanism in elevation as indicated by arrow 7 at Figure 6, and

Figure 8 is a view of the rock-shaft operating mechanism in end elevation as indicated by arrow 8 at Figure 6.

40 The improved stoker which forms the subject matter of this application comprises a structure adapted to be installed within furnace walls indicated at 10, such walls 45 being of the usual and ordinary construction and forming no part of the present invention except as they co-act with the fire-supporting and moving structure. Within the chamber formed by the walls 10, a frame work is erected, having the requisite beams 50 for supporting the grate mechanism. Upon the frame work 11 a beam 12 and retort

13 are erected in any approved manner as by casting integral with the frame members 14. The retort 13 is of general U-shape and 55 in the bottom is located a pusher rod 15, having any approved number of pusher blocks 16 secured thereto. The pusher blocks 16 are triangular in general shape, 60 presenting a substantially vertical side to the fuel, when the pusher is moving forward, and an incline to the coal when the pusher is moving rearwardly so that the fuel will ride over such pusher blocks on the return stroke.

65 To supply fuel to the retort 13, to be acted on by the pusher blocks 16, a hopper 17 is provided, communicating with a chamber 18 in which is mounted to reciprocate a ram 19. The proportion of the ram 19 to 70 the chamber 18 is such that at its rearward limit it opens the communication from the hopper 17, permitting the fuel to fall into the chamber 18, and as the ram 19 moves forward it moves the fuel from the 75 chamber 18 into the retort 13 and simultaneously closes communication with the hopper 17.

To actuate the ram, a cylinder and piston 80 20 are provided, the piston having a piston rod 21 located directly in the rear of the ram 19 and preferably below the center of such ram, in position to substantially balance the load.

The lower wall of the chamber 18 is provided with a slot 22, and a pintle 23 carried by the ram 19 extends downwardly through such slot and provides a pivot bearing for the overlapped ends of links 24.

Rigidly secured to the structure, upon 90 opposite sides of the chamber 18, are a pair of pivot blocks 25 carrying fulcrums 26 for the levers 27 each attached at one end to a link 24. At their opposite ends levers 27 are pivotally connected with engaging 95 members 28 having spaced enlargements, preferably in the form of annular collars 29.

Upon opposite sides of the frame work 14 of the retort 13 rock-shafts 30 are journaled and are provided with arms 31 having bifurcated extremities engaging upon the engaging member 28 and between the collars 29. The bifurcated extremities are provided with heads 32 of lesser diameter than the

interval between the collars 29 and adjustable filler blocks 33 are interposed, upon either side selectively of the heads 32, to vary the stroke of the arms 31 and therefore the amplitude of oscillation of the rock-shafts 30.

At Figure 6 is shown diagrammatically the movement for rocking the rock-shaft 30. It will be seen that as the pintle 23 moves from the position shown in full lines to the position 23', the levers 27 have been swung to the limit of their movement to the position 27'. As the pintle 23 continues to the opposite limit of its movement at 23'' the arms 27 are again moved back to full line position, so that the levers 27 move through a complete cycle of movement at each forward or rearward movement of the ram 19 carrying the pintle 23.

The rock-shaft 30 is provided throughout a part, or parts, or its entire length, as the grate surface may require, with a radially extending rib 34, engaging notches 35 on the underside of certain grate bars 36, each resting at one end on a bearing edge 37 of the frame 14 and at the other end on the bearer bar 38. The grate-bars are caused to slide in the direction of their length on said supports and at the same time are made to rise and fall to a limited extent by the rocking motion of rib 34. All of the grate bars employed may be of the type disclosed at 36, if the conditions of operation and the fuel make it desirable but under ordinary conditions stationary grate bars 39 are employed in association with the movable grate bars 36. These stationary grate bars bear, but do not slide, upon the frame 14, being held by the lugs 40, and also bear but do not move upon the bearer bar 38. At Figure 4 the movable bars 36 and the stationary bars 39 are shown arranged in groups, but it is to be understood that the bars may be arranged in any order found desirable or convenient to be determined from the nature of the fuel and combustion required. The arrangement of the grate bars within the scope of this invention, is not in any way limited to the grouping of the bars shown, nor to the necessary use of both stationary and movable bars in the same combination.

For use with certain grades of fuel and for certain combustion requirements, slicer bars 41 are also employed. The slicer bars when used are provided with bosses 42 engaging laterally extending lugs 42' on the juxtaposed bars which may be either movable or stationary and with any approved means for actuation from the rock-shaft 30. As shown in the drawing, especially at Figure 5, the slicer bar 41 is provided with a finger 43 extending below the bars and, by means of a link 44, pivotally connected 65 with a lug 45 carried upon the rock-shaft.

It is obvious that as the rock-shaft is oscillated by the mechanism hereinbefore described the movable grate bars engaging the rib 34 will reciprocate and the slicer bars 41 will rise and fall to and from the dotted position shown at Figure 2.

To accommodate the slicer bars, the adjacent grate bars 39' are recessed as shown more particularly at Figure 4. Preferably these recessed bars are stationary and the recess is struck upon a curved line to correspond to the arc of movement of the slicer bar as indicated at the point 46 at Figure 5.

All of the bars 36, 39 and 39' are provided with ribs 46' (see Figure 5) upon opposite sides and the ribs of each bar engage against the ribs of its juxtaposed bars. By this means the fire supporting surface is divided into areas, the one disposed above the central air duct 47 and adapted to discharge air through the tuyere-openings 48 into the fuel immediately overlying the retort 13. The other area located over the encircling air duct 49 is adapted to discharge air through the intervals 50 between the several grate bars and upon opposite sides of the slicer bars 41. It is obvious therefore that by supplying air under different pressures to the air duct 47 and the duct 49 the different areas of the ignited fuel may be subjected to different air pressures. As the green fuel, when first introduced into the area of ignition, requires for coking a greater amount of air or air under greater pressure than is required to support combustion after coking, it is desirable to supply air under greater pressure to the air duct 47 than the duct 49. For this purpose the air duct 47 is in communication with the trunk-duct 51 receiving air from any usual, ordinary or convenient source of air supply. The duct 49 is in communication with or a continuation of a header-duct 52 and the passage of air from the trunk-duct 51 to the header-duct 52 is controlled by means of a valve 53 having any convenient and approved means for manipulating, as the rod 54, provided with a hand-hold 55. By regulating the orifice controlled by the valve 53 the relation of the pressure and volume between the air in ducts 47 and duct 49 may be controlled as found desirable.

At the outer or lower sides of the grate surface, ash dumps 56 are employed, carried by shafts 57, actuated in any approved manner and dumping into ash pits 58. In the trunk duct 51 a valve 59 is provided which may be of any usual and ordinary type here shown as a butterfly valve manually operable in any usual and ordinary manner here shown as by the use of the crank arm 60.

In operation the ignited fuel, upon the fuel surface, is replenished by introducing

green fuel into the hopper 17 and supplying motive fluid to the cylinder 20. The cylinder 20, with its piston, acts in the usual manner of cylinders and pistons to advance 5 the ram 19 and the pushers 16. The advance of the ram and the pushers 16 also oscillates the rock-shafts 30 to reciprocate the movable grate bars 36, if any are employed, and oscillate the slicer bars 41, if 10 any are employed. It will be noted that the levers 27, being moved through a complete cycle of movement at each movement of the ram, the rock-shafts 30 are likewise oscillated through a complete cycle of movement, that is to say, oscillated to the limit 15 of their movement in both directions. The oscillation of the rock shafts 30, to the limit of their movement in both directions, moves the movable grate bars and slicer bars, when 20 employed, through a complete cycle of their movement, so that at either limit of movement of the ram 19 the fuel supporting surface is in normal condition with the slicer bars flush with the top of the grate surface 25 and the movable grate bars returned to normal position. This feature is highly important in view of the fact that the rapidity of feed of the furnace is determined by pauses of the ram and pusher at each end of 30 the stroke, the movement in each direction being a rapid movement. The slicer bars and movable grate bars are, therefore, moved quickly to perform their functions of agitating the ignited mass, and are returned to 35 normal position to prevent the said bars from being burned out by remaining elevated out of normality and thus extending into the incandescent mass.

While the ribs 46', upon the several grate 40 bars, maintain proper division between the grate areas of low air pressure and high air pressure, even when the movable grate bars and slicer bars are out of normality, it is nevertheless desirable that, for the 45 proper and complete maintenance of such division, the grate surface and tuyere surface be maintained at normal through as large a portion of the time as possible. This desideratum also makes the double 50 action of the grate bars and slicer bars an important feature.

By the use of the low pressure ducts 49 upon opposite sides of the high pressure duct 47 communicating with each other 55 through the cross duct and the header duct 52, it is obvious that the pressure in the two low pressure areas will be balanced at all times. The control of the air by the valves 59 and 53 is such that the air is not only balanced in the low pressure ducts, but the 60 pressure in both ducts may be regulated by the proper manipulation of the valves insuring the desirable air pressure and volume 65 upon the different areas of the combustion surface.

Having thus described my said invention, what I claim as new and desire to secure by Letters Patent, is:

1. In a stoker furnace, a grate comprising longitudinally movable bars, stationary 70 bars and slicer bars interposed between certain of the stationary bars, said stationary bars having projections engaging openings in the slicer bars and providing rocking bearings therefor, substantially as set forth. 75

2. A stoker furnace provided with a fuel supporting surface comprising grates and an intermediate retort, the grates and the retort having independent sets of air passages supplying air to the fuel supporting 80 surface, a high pressure air duct disposed beneath the retort and communicating with the air passages supplying air to said retort, a low pressure air duct entirely surrounding 85 and receiving air from the high pressure air duct and supplying air to the air passages of the grates and a single valve controlling communication between the high and low pressure air ducts, substantially as set forth. 90

3. A stoker furnace comprising a retort, 95 grates extending laterally therefrom in opposite directions, a high pressure air duct beneath the retort for supplying air thereto and low pressure air ducts beneath the grates for supplying air thereto, said high and low pressure ducts being separated by a wall of single thickness comprising sides and ends and the rear end of the high pressure duct being movable to provide an adjustable communication between the high pressure and 100 low pressure ducts, substantially as set forth.

4. In a stoker furnace a retort, grates extending laterally therefrom in opposite directions, said grates comprising fixed and movable grate bars, supports for said retort 105 and grates extending transversely of the furnace chamber, means located on said transverse supports for operating said movable grate bars, a high pressure duct beneath said retort providing a high pressure area in the furnace, a low pressure duct surrounding said high pressure duct and supplying air to said grates to provide low pressure areas in the furnace, each of said ducts having side and end walls and the space 110 constituting air ducts below the transverse supports being otherwise free and the rear end wall of the high pressure duct being adjustable to regulate the passage from the high pressure duct to the low pressure ducts, 115 substantially as set forth. 120

5. In a stoker furnace, a grate comprising movable bars, stationary bars and slicer bars interposed between certain of the stationary bars, said slicer bars being pivotally supported by adjacent stationary bars, substantially as set forth. 125

6. In a furnace, fuel-supporting means comprising a high pressure area and a plurality of low pressure areas separated there- 130

- by, independent sets of air passages supplying air to the different areas, a high pressure air duct for supplying air to the intermediate set of air passages, a low pressure duct 5 for supplying air to the sets of air passages separated by the first set, and a single valve leading from the high pressure duct to the low pressure duct, substantially as set forth.

In witness whereof I have hereunto set my hand and seal at Philadelphia, Pa., this 10 15th day of December, A. D., nineteen hundred and nineteen.

JOSEPH H. ROACH. [L. s.]
